(57) **CLAIM**

The ornamental design for a letter opener and staple remover, as shown and described.

DESCRIPTION

FIG. 1 is a top, rear and right-side perspective view of a letter opener and staple remover embodying my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a perspective view similar to FIG. 1, showing the tool in an alternative configuration; and,

FIG. 9 is a perspective view similar to FIGS. 1 and 8, showing separation of a screwdriver from the body of the letter opener and staple remover.
